UNITED STATES PATENT OFFICE.

ERNEST P. SCHULTZ, OF HAMILTON, ONTARIO, CANADA.

LAMP-GLASS EXTENSION.

1,136,278.

Specification of Letters Patent. Patented Apr. 20, 1915.

Application filed March 9, 1914. Serial No. 823,475.

To all whom it may concern:

Be it known that I, ERNEST PHILIP SCHULTZ, a subject of the King of Great Britain, and a citizen of the Dominion of Canada, residing at 154 York street, in the city of Hamilton, in the county of Wentworth, in the Province of Ontario, Dominion of Canada, have invented a certain new and useful Lamp-Glass Extension, of which the following is a specification.

This invention relates to an extension for lamp glasses and it has more particular reference to such glasses as are commonly employed on coal oil lamps for domestic and general lighting.

The main object of my invention is to provide a simple and effective means whereby the lighting efficiency is considerably increased by supplying more oxygen to the flame.

A further object is to furnish a simple means whereby a great economy in fuel consumption is attained by reducing the draft tending to disturb the flame.

With these objects in view my invention consists in the novel construction of lamp glass extension hereinafter fully described and claimed in the appended claims.

The accompanying drawing is an illustration of one practical embodiment of my invention, Figure 1, being a full sized elevation thereof as adapted for the ordinary standard type of lamp glass having a corrugated upper edge. Fig. 2, is a vertical section through the same.

According to the form of my invention illustrated the extension comprises a main or cylindrical body portion of sheet metal which is adapted to seat snugly within the top of the lamp glass or chimney 2, shown in fragmentary form by the dotted lines and broken lower edge in Fig. 1.

3, 3, are claws integral with said body portion 1, adapted to firmly clamp the extension on the top of the lamp glass or chimney 2.

4, 4, are vertical projections from the up-

per edge of the body portion 1, and they have seated and secured thereon a hood or canopy 5, said canopy or hood being of concavo-convex formation and of a diameter sufficiently large to project beyond the exterior peripheral wall of the body portion 1. It is to be noted that the projections 4, 4, and canopy or hood 5, form air spaces or draft openings 6, 6. Also that the body portion 1, claws 3, 3, and projections 4, 4, are all stamped out from one sheet of metal and then fashioned as shown the joining edges being brazed or secured together. The canopy 5, effectively prevents lateral or down drafts through the openings 6, 6.

From the foregoing it will be seen that by my invention I provide a neat and effective device for the purposes specified, and I do not limit myself to the precise details or shape and proportions of the parts illustrated and described.

Having thus described my invention what I claim as new and desire to secure by Letters Patent, is:-

An extension for lamp glasses embodying an imperforate sheet metal cylindrical body portion substantially coequal in diameter with the upper edge of the lamp glass, said body portion having integral claws bent backwardly thereupon and then bent into hook formation to adapt them to engage over the usual enlarged edge of a lamp glass while the lower edge of the body portion enters within said upper edge of the lamp glass and lies but slightly below the horizontal plane thereof, upright extensions carried by the upper edge of the body portion and a canopy carried by said extensions which is of greater diameter than said body portion.

Signed at Hamilton, county of Wentworth, Province of Ontario, Dominion of Canada, this 20th day of February, A. D. 1914.

E. P. SCHULTZ.

In the presence of—

ALFRED T. BRATTON,
GERTIE NICHOLSON.
